(57) **CLAIM**

The ornamental design for a weed cutting blade, as shown and described.

DESCRIPTION

FIG. 1 is a top perspective view of the invented weed cutting blade design.

FIG. 2 is a top view of the weed cutting blade design of FIG. 1.

FIG. 3 is a rear view of the weed cutting blade design of FIG. 1.

FIG. 4 is a front view of the weed cutting blade design of FIG. 1.

FIG. 5 is a right side view of the weed cutting blade design of FIG. 1, wherein the left side view will be a mirror image of the right side view.

FIG. 6 is a top perspective view of a weed cutting blade with rounded tips

FIG. 7 a top view of the weed cutting blade design of FIG. 6.

FIG. 8 is a rear view of the weed cutting blade design of FIG. 6.

FIG. 9 is a front view of the weed cutting blade design of FIG. 6.

FIG. 10 is a right side view of the weed cutting blade design of FIG. 6, wherein the left side view will be a mirror image of the right side view.

FIG. 11 is an edge view of the weed cutting blade design of FIGS. 1 and 6 showing fibers embedded in the blade; and, FIG. 12 is an environmental top perspective view of the weed cutting blade design of FIG. 1. The weed cutting device shown in broken lines forms no part of the claimed design.
